12 Claims. (Cl. 196—52)

1

This invention has to do with a method and apparatus for conversion of fluid hydrocarbons in the presence of a moving particle form solid contact material which may or may not be catalytic in nature. Exemplary of the hydrocarbon conversion which may be conducted by this method and apparatus are the catalytic aromatization, hydrogenation, dehydrogenation, polymerization, isomerization, alkylation, dealkylation, reforming, hydroforming, treating, desulfurization and cracking of hydrocarbon fractions. Also exemplary are the viscosity breaking, cracking and coking of heavy liquid hydrocarbons in the presence of a hot solid inert material. This invention is particularly concerned with processes wherein the contact material moves cyclically through a conversion zone wherein it flows as a substantially compact column of moving solid particles while being contacted at suitable elevated temperatures with fluid hydrocarbons either in the gaseous or liquid phase or both to effect their conversion and then through a revivification zone wherein it flows as a substantially compact column while being contacted with a suitable revivifying gas which in many instances may be air acting to burn off from the contact material a carbonaceous contaminant deposited thereon during the hydrocarbon conversion. When the contact material employed is catalytic in nature it may take the form of natural or treated clays such as fuller's earth and Super Filtrol, bauxites, activated alumina, activated charcoal, inert carriers bearing deposits of catalytic metallic oxides, or synthetic associations of silica, alumina or silica and alumina to which may be added small percentages of other materials such as certain suitable metallic oxides. When the contact material employed is noncatalytic in nature, i. e., inert to the reaction, it may take any of a number of forms such as granules or balls of metallic material or refractory material such as Corhart material, mullite, Carborundum or zircon fabas (a complex zirconium silicate); the material used preferably having a high thermal heat capacity and being highly resistant to breakage, cracking and abrasion. In any case, the particle size of the solid material employed should fall broadly within the range 2 to 100 mesh by Tyler Standard Screen Analysis and preferably within the range of about 4 to 20 mesh.

One of the most important processes for which this invention is adapted, is the cracking conversion of high boiling fluid hydrocarbons to lower boiling gaseous hydrocarbon products con-

2

taining gasoline and/or lower boiling hydrocarbon products in the presence of a hot particle form contact mass material. During this particular reaction, as is the case with many other hydrocarbon conversions, a carbonaceous contaminant is deposited upon the particle form solid. If the contact material is catalytic in nature, the contaminant deposit substantially reduces its catalytic activity. If the contact material is non-catalytic in nature, the contaminant deposit may gradually increase the particle size of the contact material to an undesirable degree while at the same time small particles of coky material having an undesirably small diameter tend to accumulate in the moving contact mass. In any event, it is usually desirable to effect the removal of the contaminant deposit from the contact material. This may best be accomplished in a revivification chamber separate from the conversion chamber. In the case of inert contact materials, the carbonaceous contaminant may in many cases tend to break off the contact material particles and be susceptible to removal from the mass by entrainment in a suitable gas passed through the mass. On the other hand, steam and/or air may be introduced into the hot contaminant bearing contact mass to cause the carbonaceous contaminant to undergo a producer or water gas reaction. Other reactions are also available. In the case of catalysts, it has been found best to regenerate the catalyst by blowing an oxygen containing gas therethrough to burn off the contaminant, while withdrawing excess combustion heat from the mass in order to prevent the catalyst temperature from rising to a heat damaging level. Commercially, in order to permit a practical overall unit structural height, it has been found desirable to position the conversion and revivification vessels side by side at substantially the same elevational level and to provide two contact material conveyors, one for conveying used contact material from the conversion vessel to the revivification vessel and one for conveying revivified contact material from the revivification vessel back to the conversion vessel.

The instant invention broadly involves a method and apparatus in a continuous cyclic conversion process whereby used contact material from the conversion vessel and revivified contact material from the revivification vessel may be passed into separate pocket compartments in the buckets of a single continuous bucket elevator to be conveyed upwardly to-

gether in the single elevator casing and to be separately discharged into passages feeding the revivification and conversion vessels. It has been found that this improved method and apparatus results in lower initial apparatus cost, lower maintenance and operational costs, a substantial decrease in undesirable heat loss from the contact material streams passing between vessels and an overall more compact cyclic conversion unit and better adapted to the requirements of the small refiner than those known heretofore.

A major object of this invention is the provision in a cyclic process wherein contact material is passed cyclically through conversion and revivification zones of an improved method and apparatus for accomplishing the passage of contact material between said zones.

Another object of this invention is the provision of a practical, economical continuous catalytic hydrocarbon conversion system suitable to the requirements of small refiners.

Another object is the provision of an improved method and operation for the conversion of fluid hydrocarbons in the presence of a cyclically moving particle form solid contact material.

Another object is the provision of a method and apparatus for conveying particle form contact material between side by side separate hydrocarbon conversion and contact material revivification zones which permits a substantial reduction in heat loss from the cyclically moving contact material stream as compared with that occurring in present cyclic conversion processes.

These and other objects of this invention will become apparent in the following discussion of the invention. Before proceeding with this discussion several expressions used herein in describing and claiming this invention may be defined. The expression "gaseous" as used herein is intended broadly as meaning that the material involved exists in the gaseous phase under the particular operation conditions of temperature and pressure involved regardless of what may be the normal phase of that material under ordinary atmospheric conditions. The expressions "revivifier" or "revivification vessel" are intended to broadly cover a vessel in which used contact material from a conversion vessel may be made suitable for reuse in said conversion vessel regardless of the exact nature of the reaction occurring in the revivification vessel or regardless of whether or not any chemical reaction occurs therein at all. The term "revivifying gas" is employed in a similarly broad sense as meaning any gas which is suitable for restoring the contact material to a condition for practical reuse in the conversion zone. The expressions "heat damaging level" or "heat damaging temperature" are intended to mean a temperature or a temperature level which would cause substantial permanent impairment of that property or of those properties which render the particular contact material employed useful for the particular hydrocarbon conversion involved. The expression "fluid" is intended to mean material either in the liquid or gaseous phase or in mixed phase. The expression "contact material" is intended to broadly cover solid materials which are suitable for use in the particular conversion process involved regardless of whether or not said solid materials are catalytic in nature.

The invention may be best understood by reference to the drawings attached hereto of which Figure 1 is an elevational view showing a cyclic

conversion process arranged according to the teachings of this invention. Figure 2 is an elevational view, partially in section, showing an assembly view of the elevator portion of the apparatus combination shown in Figure 1. Figure 3 is a sectional view taken along line 3-3 of Figure 2. Figure 4 is an isometric view showing the upper section of the elevator casing of Figure 2. Figure 5 is a sectional view taken along line 5-5 of Figure 2, Figure 6 is a sectional view of a bucket used in the elevator shown in Figure 2. Figure 7 is a side view of the bucket taken along line 7-7 of Figure 6, Figure 8 is a sectional view of the bucket taken along line 8-8 in Figure 6. Figure 9 is an isometric view of the same bucket, Figure 10 is a detailed view showing elevator chain construction and details of bucket attachment thereto. Figure 11 is an isometric view of a modified bucket construction and Figure 12 is a detailed view showing the attachment of the bucket shown in Figure 11 to an elevator chain. All of these drawings are highly diagrammatic in form.

Turning now to Figure 1, we find a conversion vessel 20, a revivification vessel 21 and a single dual conveyor or elevator 22. The conversion vessel may be of any suitable cross-sectional shape, preferably circular and should be adapted to permit contact of a fluid reactant therein with a particle form contact material moving therein as a substantially compact column. Fluid hydrocarbon charge may be pumped by pump 23 through heater 24 which may be of suitable conventional construction adapted to merely heat or to heat and vaporize the hydrocarbon charge to the desired convertor inlet conditions. The prepared charge passes into the conversion vessel through inlet conduit 25. An outlet 26 is provided near the lower end of the conversion vessel for withdrawal of gaseous hydrocarbon products. The products are passed to a suitable product purification and recovery system 27 which may be of conventional type. Suitable gas-solid disengaging means should be provided within the vessel in communication with outlet 26. Above the vessel 20 is provided a contact material feed or surge hopper 28 from which contact material may be supplied to the conversion vessel through a feed leg 29. The feed leg should be of sufficient vertical height to insure continuous contact material flow into the conversion vessel against the gaseous pressure therein. A drain conduit 30 is provided at the bottom of vessel 20 for contact material withdrawal. The drain conduit connects into a depressuring chamber 31 wherein the gaseous pressure on the contact material may be released, the gas leaving through outlet 32. Suitable flow control means indicated by the dotted lines 33-35 inclusive may be provided near the bottom of vessel 20 to permit withdrawal of contact material at a uniform rate from all portions of the chamber cross-sectional area thereabove. It will be understood that other suitable means and arrangements for contact material and reactant introduction and withdrawal to and from the conversion vessel other than that specifically described hereinabove are contemplated to be within the scope of this invention. The revivification vessel similarly may be provided with any of a number of suitable arrangements for contact material and gas introduction and withdrawal. The arrangement shown is a preferred multi-stage kiln arrangement which has been found particularly useful for regeneration of

catalysts. Air is admitted from inlet 33 to vertical manifold 34 from which it passes into the vessel 21 at a plurality of spaced levels through a plurality of inlets 35 bearing flow control valves 37. Flue gas is withdrawn at a plurality of intermediate levels through outlet pipes 36 which connect into outlet duct 38. A suitable heat exchange medium entering through manifold 42 and spaced apart individual inlet pipes 41 may be passed through communicating heat transfer tubes (not shown) at a plurality of spaced levels in the vessel 21. The heat exchange fluid may be withdrawn from the heat transfer tubes (not shown) through outlet pipes 40 into outlet manifold 39. Any of a number of heat exchange fluids may be employed such as water, steam, certain low melting point metallic alloys and certain mixtures of fused inorganic salts. The heat exchange fluid is passed through the tubes under such conditions as to control the catalyst at a temperature sufficiently high to permit rapid contaminant combustion but insufficiently high to cause heat damage to the catalyst. Contact material may be admitted to the upper end of the vessel 21 via conduits 43 and 44 and withdrawn therefrom through conduit 45 bearing flow control valve 46. The elevator 22 which will be described in detail hereinafter is of the continuous bucket type, the buckets being divided into separate compartments by suitable partitioning. A partitioned inlet chute 47 is provided near the lower end of the elevator, said chute having a plurality of separate feed lanes therein corresponding to the plurality of pockets in each bucket. A similarly partitioned outlet chute 48 is provided near the upper end of the elevator casing. In operation, used contact material from the conversion vessel may pass from the depressuring pot 31 through conduit 49 and flow control valve 50 into conduits 55 and 56 into two outside feed lanes in chute 47 by which it is directed into certain of the pockets in the elevator buckets passing upwardly past the feed chute. Similarly, revivified contact material may pass through conduit 45 into the remainder of the feed lanes in chute 47 and thence into the remainder of the pockets in the elevator buckets. Revivified and used contact material is carried together in the separate pockets of the elevator buckets upwardly to the upper section of the conveyor casing where the used contact material is discharged into two discharge lanes in the chute 48 feeding conduits 52 and 53, which conduits converge into conduit 43 feeding the vessel 21. Revivified contact material is discharged from the buckets into a central discharge lane in chute 48 from which it passes through conduit 57 into feed hopper 28 feeding the conversion vessel 20. It will be understood that such expressions as "passing the revivified contact material from the conveying zone to the conversion zone" and "passage defining means for flow of regenerated contact material from the remainder of said lanes in said discharge chute to said conversion vessel" or "passage defining means for flow of regenerated contact material from the remainder of said lanes in said discharge chute to said inlet to said conversion vessel," employed in the claims are used in a broad sense as covering a feed duct connected directly from the elevator discharge chute to the top of the conversion vessel or as covering a duct delivering contact material to a feed hopper, the feed hopper and a duct ex-

tending from the feed hopper to the conversion vessel. The same is true of language regarding delivery of contact material from the elevator to the revivification vessel. In Figure 1, a surge or feed hopper is incorporated in the upper section of the vessel 21 as indicated by the dotted lines 59 and 60. The operating pressures in the conversion vessel, revivification vessel and elevator casing may vary depending upon the particular conversion operation involved. In the catalytic cracking conversion of hydrocarbons it has been found convenient to operate the conversion vessel under pressures of the order of 5 to 15 pounds per square inch gauge, and to operate the revivification vessel, elevator casing and convertor feed hopper at substantially atmospheric pressure or at a pressure only slightly above atmospheric, for example, $\frac{1}{8}$ to 1 pound per square inch gauge. Thus, vents 61, 62 and 63 are provided on the hopper 28, elevator casing 22 and a revivification vessel 21 respectively. In view of the above, it will become apparent that it is of considerable importance that proper provision be provided to prevent the flow of gaseous hydrocarbons into the conveyor casing. This is accomplished by the provision of an inert gaseous seal between the conversion vessel 20 and the elevator casing 22. An inert gas such as steam or flue gas may be introduced into the top of vessel 20 through conduit 64 at a rate controlled by diaphragm valve 65 operated by differential pressure control mechanism 66 such as to maintain an inert gaseous pressure adjacent the upper end of vessel 20 greater than the pressure of the hydrocarbon reactant in the conversion zone directly therebelow. Thus, the escape of gaseous hydrocarbons through the feed conduit 22 and hopper 28 to the atmosphere or to the elevator casing is prevented. An inert purge gas such as steam or flue gas may be admitted through conduit 68 into the lower section of the vessel 20 below the conversion zone to purge gaseous hydrocarbons from the outflowing used contact material and to prevent substantial escape of gaseous hydrocarbons through conduit 38. Some inert gas will pass downwardly through the contact material in conduit 38. In many operations, the amount of such inert gas may be sufficient to cause substantial contact material spillage into the foot portion of the conveyor casing 22 and to interfere with the flow of used contact material into the proper bucket pockets. In such operations, this difficulty may be avoided by separating the inert gas from the contact material in the depressuring pot 31 which is operated under a pressure near that in the conveyor casing. While usually it has been found unnecessary in catalytic cracking operations, in some operations it may be desirable also to substantially prevent the flow of revivification gas into the elevator casing. This may be accomplished by the introduction of a suitable inert seal gas into the upper and lower ends of vessel 21 through conduits 63 and 70, respectively. It is usually desirable to maintain an inert gaseous atmosphere within the elevator casing 22. This may be accomplished by introduction of an inert gas such as steam or flue gas through conduit 71 near the lower end of casing 22. The inert gas may be withdrawn through vent 62 or through vent 61 and/or 63. A certain amount of undersized material tends to accumulate in the cyclically moving contact material stream. These fines may be removed by passage of a portion of the unregen-

erated contact material stream through conduit 75 into an elutriator 76 through which it is "rained" countercurrently to an upwardly moving stream or flue gas entering from duct 38 through duct 77. Cleaned contact material passes from the bottom of elutriator through conduit 78 to join the main contact material stream in the upper end of vessel 21. Fines entrained in flue gas pass from the upper end of elutriator 76 through duct 78, which joins manifold duct 38 and connects into cyclone separator 80 through duct 81. Flue gas is withdrawn from the separator at 82 and fines at 83.

Operation by the above method permits a substantial reduction in the total heat loss from the contact material passing between conversion and regeneration chambers over the heat loss occurring when two elevators are employed. This is of considerable importance in operations wherein the heat stored in the contact material leaving the regenerator is used in part to supply heat for the hydrocarbon conversion and in operations wherein the used contact material exists at temperature levels not much above the minimum temperature required to initiate contaminant combustion in the regenerator. Moreover, inasmuch as a large part of the power consumption required for bucket elevator operation is used to overcome friction of the moving parts, the use of one instead of two elevators results in a substantial reduction in conveying cost as well as an obvious reduction in initial conveyor cost. It has been further found that the arrangement described hereinabove permits a much more compact arrangement of the entire unit resulting in a decrease in the amount of ground area required. Due to these advantages the method and apparatus of this invention make possible the provision of a compact, economical, small capacity cyclic conversion process which is particularly well adapted for the requirements of small refineries.

Turning now to Figures 2, 3, 4 and 5, which may be best considered together for a more detailed study of the construction of the dual purpose conveyor, it will be seen that the casing is made up of a foot portion, a head portion and an intermediate portion. The casing may be made up in a single section but it is preferably made up of a plurality of flanged sections and generally at least of three sections, namely, a head section, an intermediate section and a foot section. Within the casing is provided an endless series of buckets 90 which preferably overlap to a limited extent substantially as shown in Figure 2. A head shaft 91 passes through the casing in the head portion and two spaced apart wheels 92 and 92' are provided on the head shaft. Continuous chains 93 and 93' are trained over the wheels 92 and 92' so as to form a loop in the head portion of the casing and a second loop in the foot portion. The chains may be guided by guides indicated by the dotted lines 94 attached along opposite sides of casing 22 and by means of the guide wheels 98 at the foot loop. In some constructions the wheels 98 may be omitted. The head shaft is driven by an externally located drive wheel 95 driven in turn through chain 96 by motor 97. The drive wheel is removed from shaft 91 in Figure 4 to permit a view of support bearings 100. A variable speed drive may be provided in many cases. The buckets 90 may take any of a number of cross-sectional shape, a preferred shape being approximately that indicated in Figure 6. The buckets are attached on their

opposite ends to the two chains 93 and 93' in such a manner as to open outwardly of their closed path of travel and in such a manner as to open outwardly and upwardly as they move upwardly adjacent that side of the casing 22 into which the feed chute 47 connects and as to be inverted as they move downwardly adjacent that side of the casing 22 into which the discharge chute 48 connects. The buckets are further so shaped and fastened to the chains 93 and 93' that in passing over the head loop or the wheels 92 and 92', each bucket discharges contact material onto one side of the inverted bucket moving immediately before said first named bucket and the side of the inverted bucket receiving the discharged solid is so sloped as to direct the contact material into the discharge chute 48. It will be noted that the discharge chute extends into the conveyor casing to such an extent that the chute opening is close to the edges of the buckets as they pass downwardly in their path. The arrangement is such that the contact material is poured from the buckets into the discharge chute rather than being thrown as is the case in centrifugal type bucket elevators. The construction described hereinabove permits discharge of contact material from the buckets into the discharge chute with very little spillage of contact material occurring. The feed chute 47 similarly extends a short distance into the casing 22 so as to terminate just opposite the edge of the open tops of the buckets 90 so that contact material pours directly from chute 47 into the upwardly moving buckets 90 without substantial spillage of contact material into the foot section of the casing.

For a study of the bucket construction, Figures 6, 7, 8 and 9 should be considered along with Figures 2, 3, 4 and 5. Each bucket is provided with partitioning to divide it into a plurality of separate side by side solid carrying pockets or compartments. A preferred construction is shown wherein each bucket is divided by partitions 101 and 102 into two small end pockets 103 and 104 and a larger pocket 105 therebetween having approximately the same capacity as the sum of the capacities of the two end pockets. A plurality of partitions 106 and 107 are provided in the feed chute 47 to divide it into three separate feed lanes 108, 109 and 110 corresponding to and adapted to deliver solid into the three bucket pockets 103, 104 and 105 respectively. Similarly partitions 111 and 112 divide the discharge chute 48 into three separate discharge lanes 113, 114 and 115 corresponding to bucket pockets 103, 104 and 105 respectively. Likewise vanes 116, 117, 118 and 119 are provided on the side of each bucket onto which contact material is discharged to provide three lanes for contact material flow corresponding to the three discharge lanes in discharge chute 48. It will be further noted that partitions 101 and 102 in the buckets 90 are flared as they approach the opening in the bucket in such a manner as to divert the contact material discharging from any of the pockets 103, 104 or 105 away from that discharging from an adjacent pocket and into the proper lane of flow on the side of the bucket moving immediately therebefore. Moreover, the vanes 117 and 118 on the solid receiving side of each bucket are also flared as they approach the edge of the bucket moving nearest the discharge chute 48 so as to divert the solid flow from the lanes on the inverted bucket sides into the proper corresponding discharge lanes in chute 48. Similarly, the

partitions 106 and 107 in the feeding chute 47 are flared as they approach the discharge edge of the chute so as to divert the solid flow from each of the feed lanes 108, 109 and 110 into the corresponding pockets in the buckets 90.

The preferred bucket construction and pocket arrangement and feed and discharge chute arrangement described hereinabove permits the introduction of contact material existing at the same temperature, into the two end pockets of the buckets which pockets are adjacent the two elevator chains. In the arrangement shown, used contact material is carried in the end pockets 103 and 104 and revivified contact material is carried only in the intermediate pocket 105. By this arrangement only contact material of the same temperature is adjacent the two elevator chains so that the temperature of the chains will be maintained equal. It will be understood that if the arrangement were such that the contact material fed to one end of the bucket were regenerated contact material existing at 1050° F., for example, while the contact material fed to the other end of the bucket were spent contact material existing at 800° F., the two elevator chains would operate at different temperatures causing unequal chain expansion. This unequal chain expansion would result in serious mechanical difficulties and in warping of the buckets. It will be understood that by proper reversal in the positions of the conduits supplying the feed chute 47 and draining the discharge chute 48, the two end compartments of the buckets may be caused to carry only regenerated contact material while spent contact material is carried in the intermediate compartment. Both arrangements are intended as being within the scope of this invention.

Turning to Figure 10, there is shown a detailed view of a section of one elevator chain 93' and of the bucket attachment thereto. It will be seen that the chain is a knuckle chain of the offset type. Each link has near one end a knuckle 120 in which is a bushing indicated by dotted lines at 121. A chain pin 122 fits through the bushing 121 and through holes in the offset side bars of the next link. A keeper bar 123 may be employed to hold the chain pin in place. To each end of the buckets is welded or bolted an attachment bar or bracket 124 which is in turn bolted to one of the chains such as 93'.

A modified form of bucket construction is shown in Figures 11 and 12. In these figures a bucket 130 having an angular cross-sectional shape is shown. One side of the bucket 131 is bolted by bolts 132 to the conveyor chain 93. The bucket side 131 projects a short distance beyond the line of intersection of the other side of the bucket so as to provide an overlap plate 133. Partitions 134 and 135 are provided within the bucket and vanes 136, 137, 138 and 139 along one side of the bucket similar to the partitions and vanes provided for the bucket construction shown in Figures 6-9, inclusive.

The operating conditions to be employed in the method and apparatus of this invention may vary widely depending upon the particular process application involved and the structural material used for the apparatus must necessarily be chosen with reference to the operating conditions involved. As an example of typical operating conditions in a hydrocarbon catalytic cracking conversion operation, the catalyst to oil ratio passed through the conversion vessel may be of the order of 1 to 10 parts by weight of catalyst per part of oil. The oil space velocity may be of the order

of 0.5 to 5.0 volumes of oil charge (measured as a liquid at 60° F.) per volume of catalyst in the conversion zone. The catalyst temperature within the conversion zone may fall within the range about 800° F. to 1000° F. and in the regeneration zone between about 800° F. to 1200° F. The elevator bucket size should be so chosen in relation to the rate of bucket travel and the rate of contact material cyclic flow that the buckets are never overfilled and are preferably only about 60 per cent to 90 per cent filled with contact material.

It will be understood that the particular details of apparatus construction and of operating conditions and application of this invention given hereinabove are exemplary in nature and are not to be construed as limiting the scope of this invention except as it may be limited by the following claims.

I claim:

1. A method for conducting conversion of fluid hydrocarbons in the presence of a moving particle form contact material which method comprises: passing particle form contact material at a temperature suitable to support said fluid hydrocarbon conversion downwardly through a conversion zone as a substantially compact column, passing fluid hydrocarbons under suitable conversion conditions of temperature and pressure into contact with said contact material in said conversion zone, withdrawing gaseous hydrocarbon products from said conversion zone, withdrawing a stream of used contact material from said conversion zone, releasing the gaseous pressure on said stream and thereafter passing said contact material into a confined conveying zone, conducting said used contact material upwardly within said conveying zone, passing said used contact material from said conveying zone to a separate confined contact material revivifying zone, contacting said contact material with a suitable revivifying gas in said revivifying zone while maintaining it within a suitable revivifying temperature range, passing revivified contact material at a substantially higher temperature than said used contact material from the lower section of said revivifying zone into said conveying zone, conveying said revivified contact material upwardly through said conveying zone along with and in heat conductive relationship with said used contact material while maintaining the used and revivified contact materials separated, separately passing said revivified contact material from said conveying zone to the upper section of said conversion zone and maintaining a blanket of an inert gas adjacent the upper section of said conversion zone.

2. An apparatus for conversion of fluid hydrocarbons in the presence of a moving particle form contact material which apparatus comprises: a substantially vertical reaction vessel, means to introduce fluid reactant thereto and means to withdraw gaseous conversion products therefrom, a separate regeneration vessel, means to introduce regeneration gas thereto and means to withdraw gas therefrom, an elongated upright elevator casing having head section and foot section within said casing, an endless series of articulated buckets, means to support said buckets and to cause them to pass in a closed path, said path having a loop in said head section and in said foot section and said buckets being inverted as they move downwardly in their path and substantially upright as they move upwardly, partitioning in said buckets dividing each bucket into

a plurality of contact material conveying compartments, conduit means for withdrawal of contact material from the lower end of said conversion vessel, a depressuring chamber on said conduit means adapted to permit release of the gaseous pressure on said contact material, a gas vent conduit connecting into the upper section of said depressuring chamber and communicating on its other end with a location of lower pressure than said depressuring chamber, passage defining means extending from said depressuring chamber to a location in said elevator casing near the lower end thereof, adapted to direct the flow of used contact material into certain of said plurality of compartments in said buckets, passage defining means adapted for passage of regenerated contact material from the lower end of said regeneration vessel into the remainder of said compartments in said buckets at a location near the lower end of said elevator casing, a discharge chute near the upper section of said casing but below said loop in said head section, said discharge chute being partitioned to provide a plurality of separate lanes adapted to catch the used and regenerated contact material discharge from said separate compartments in said buckets in separate discharge lanes, passage defining means for flow of used contact material from the lane in said discharge chute containing the same to said regeneration vessel, a feed hopper adapted to supply contact material to said conversion vessel, passage defining means for flow of regenerated contact material from the lane in said discharge chute containing the same to said feed hopper and means to introduce an inert gas into the lower section of said elevator casing.

3. The method of operating a cyclic process for conversion of fluid hydrocarbons wherein moving particles of solid contact material are intimately contacted with a moving stream of fluid hydrocarbons in a confined conversion zone to effect the conversion thereof to lower boiling gaseous hydrocarbons and wherein the used contact material from said conversion zone is passed through a revivification zone to be contacted with a combustion supporting gas at controlled elevated temperatures in order to burn off from said contact material contaminant deposited thereon by said hydrocarbon conversion which method comprises: moving an endless series of buckets continuously through a closed path within an elongated confined conveying zone causing said buckets to move upwardly along one side of said conveying zone and downwardly along the opposite side of said conveying zone and to loop near the upper and lower ends of said conveying zone, causing said buckets to open to the outside of said closed path of travel as they move upwardly in said path, withdrawing used contact material from said conversion zone and flowing it into said conveying zone near its lower end at a location adjacent one edge of and outside of the closed path of bucket travel while directing the flow so that said used contact material passes into the outwardly opening upwardly moving buckets, passing revivified contact material at a temperature substantially above that of said used contact material and above the minimum required to initiate combustion of said contaminant from said revivification zone into said conveying zone near its lower end at a location adjacent one edge of and outside of said closed path of travel while directing the flow so that said revivified contact material passes into a different

section of said outwardly opening upwardly moving buckets than said used contact material and at the same time maintaining the used contact material delivered to said buckets in indirect heat transfer relationship with but separate from the revivified contact material delivered simultaneously to the same buckets, and discharging said buckets near the upper end of said conveying zone at locations outside of closed path of travel and adjacent one edge thereof while directing the flow of said used and of said revivified contact material so that said used contact material passes separately to said revivification zone and said revivified contact material passes separately to said conversion zone.

4. In a process for conversion of fluid hydrocarbons in the presence of a moving particle form contact material wherein the moving particles 20 of contact material are intimately contacted with a moving stream of fluid hydrocarbons in a confined conversion zone to effect the conversion thereof to lower boiling gaseous hydrocarbons at suitable conversion temperatures and the used 25 contact material from the conversion zone is passed through a revivification zone to be contacted with a combustion supporting gas at controlled elevated temperatures substantially above said conversion temperatures in order to burn off 30 from said contact material contaminant deposited thereon by said hydrocarbon conversion and wherein the contact material is conveyed between said conversion and revivification zone in a confined conveying zone by an endless series 35 of buckets moved and supported through a closed path forming a loop near the upper end of said conveying zone and a second loop near the lower end thereof by endless chains attached to the two opposite ends of the buckets, said buckets being 40 divided into three side by side compartments, one central compartment and one compartment on each end of the buckets being attached to a chain, the improvement comprising: withdrawing revivified contact material from said revivification 45 zone and flowing it into the central compartments of said buckets near the lower end of said conveying zone, withdrawing the used contact material at a temperature substantially below that of said revivified contact material from said 50 conversion zone and flowing it into the two end compartments of each of said buckets where it is in indirect heat transfer relationship with said chains, conveying said used and revivified contact material upwardly within said conveying 55 zone, and causing said used and revivified contact material to discharge from said buckets at a location near the upper end of said conveying zone while baffling the flow thereof so that said used contact material passes separately to said 60 revivification zone and said revivified contact material passes separately to said conversion zone.

5. The method of operating a cyclic process for conversion of fluid hydrocarbons in the presence 65 of a moving particle form contact material which comprises passing said contact material through a conversion zone wherein it contacts fluid hydrocarbons under conversion conditions to effect the conversion thereof and through a regeneration zone wherein it is contacted with a revivifying gas under elevated temperatures, withdrawing a stream of used contact material from the conversion zone, withdrawing a stream of revivified contact material from said revivifying zone, continuously dividing and collecting said streams of

used and revivified contact material simultaneously into successive small portions, conveying the portions of used and revivified contact material collected simultaneously together in conductive heat transfer relationship with each other through a confined conveying zone, all of the successive portions being successively conveyed in like manner, continuously merging the successively conveyed portions of used contact material into a single stream and passing said stream to the revivifying zone, and separately continuously merging the successively conveyed portions of revivified contact material into a single stream and passing said last named stream to said conversion zone.

6. A method of conducting a cyclic operation at elevated temperatures for the conversion of hydrocarbons wherein moving solid contact material particles are intimately contacted with a moving stream of hydrocarbons to be converted in a confined conversion zone resulting in a deposition of carbonaceous contaminant on the contact material and wherein used contact material from said reaction is revivified by intimately contacting the spent particles with a gaseous revivifying agent to burn off the contaminant while both are moving in a separate confined regeneration zone which comprises: passing revivified contact material from said revivifying zone into an elongated confined conveying zone near one end thereof at an elevated temperature substantially above the minimum temperature required for the contaminant burning, conducting said revivified contact material through said conveying zone and conducting it from a location near its opposite end to said conversion zone, passing used contact material at a temperature substantially below that of said revivified contact material from said conversion zone into said conveying zone near the location of introduction of said revivified contact material, conducting said used contact material through said conveying zone along with and in indirect heat transfer relationship with said revivified contact material while maintaining it separate therefrom so as to effect its transfer without excessive drop in temperature, and conducting said used contact material from said conveying zone to said revivifying zone.

7. The method of operating a cyclic process for conversion of fluid hydrocarbons wherein moving particles of solid contact material are intimately contacted with a moving stream of fluid hydrocarbons in a confined conversion zone to effect the conversion thereof to lower boiling gaseous hydrocarbons and wherein the used contact material from said conversion zone is passed through a revivification zone to be contacted with a combustion supporting gas at controlled elevated temperatures in order to burn off from said contact material contaminant deposited thereon by said hydrocarbon conversion which method comprises: moving an endless series of buckets continuously through a closed path within an elongated confined conveying zone with said path forming a loop near the upper end of said zone and a second loop near the lower end of said conveying zone, causing said buckets to open outwardly of their closed path of travel as they move upwardly, withdrawing used contact material from said conversion zone and flowing it into said conveying zone near its lower end while directing the flow so that said used contact material passes into said buckets along only a portion of their lengths, passing revivified contact mate-

rial existing at a temperature substantially above that of said used contact material from said revivification zone into said conveying zone near its lower end while directing the flow so that said revivified contact material passes into only the remaining portion of the lengths of said buckets, maintaining the used and revivified contact material separated but in indirect heat exchange relationship with each other in said buckets

5 whereby the net heat loss from the used contact material during its transfer is restricted and discharging said used and revivified contact material from said buckets near the upper end of said conveying zone while baffling the flow thereof so that said used contact material passes separately to said revivification zone and said revivified contact material passes separately to said conversion zone.

8. The method of operating a cyclic process for conversion of fluid hydrocarbons wherein moving particles of solid contact material are intimately contacted with a moving stream of fluid hydrocarbons in a confined conversion zone to effect the conversion thereof to lower boiling gaseous hydrocarbons and wherein the used contact material from said conversion zone is passed through a revivification zone to be contacted with a combustion supporting gas at controlled elevated temperatures substantially above those in said conversion zone in order to burn off from said contact material contaminant deposited thereon by said hydrocarbon conversion which method comprises: moving an endless series of buckets continuously through a closed path within an elongated confined conveying zone, causing the buckets to move upwardly in one half of the path length and downwardly in the other half of the path length, supporting said buckets on two opposite ends thereof so that the buckets moving upwardly are open to receive solids from the outside of their path of travel, withdrawing a stream of used contact material from said conversion zone, continuously dividing said stream into two secondary streams and directing said secondary streams into opposite end portions of the upwardly moving buckets within the lower section of said conveying zone, withdrawing a stream of revivified contact material from said revivification zone at a temperature substantially

20 above that of said used contact material and directing the stream of revivified contact material into a central portion of said buckets intermediate said end portions, maintaining the revivified contact material in the central portions of said buckets separated from used contact material in the end portion of said buckets while conveying the contact material upwardly in said buckets, and discharging said used and revivified contact material from said buckets near the upper end of said conveying zone at a location outside of said closed path of travel while directing the flow thereof so that said used contact material passes separately to said revivification zone and said revivified contact material passes separately to said conversion zone; and at the same time maintaining an inert gaseous seal between said confined conveying zone and said conversion zone so as to substantially prevent the flow of gaseous hydrocarbons from said conversion zone into either end of said conveying zone.

25

9. In a system for conversion of hydrocarbons in the presence of a moving contact material the apparatus comprising, two separate contacting chambers, one being an upright reaction chamber having a contact material inlet at its upper

end and a contact material outlet at its lower end and the other being an upright regeneration vessel having a contact material inlet at its upper end and a contact material outlet at its lower end, a separate upwardly extending elevator casing, a head shaft having thereon a pair of spaced drive wheels passing across its upper section, spaced endless chains trained over said wheels to form a loop in the upper section of said casing and a second loop in the lower section of said casing, a series of buckets arranged between and attached on their opposite ends to said chains, so as to be in conductive heat transfer relationship at their ends with said chains, said buckets opening toward the outside of their path of travel and being inverted during that portion of the path of travel wherein they move downwardly, upright partitions in each bucket dividing it into at least three separate, side by side contact material carrying compartments, one compartment being at each end of said bucket adjacent its connection to a chain and any remaining compartments lying between the two end compartments, a contact material feed chute connecting into the lower section of said elevator casing on that side nearest adjacent the upwardly moving buckets, said chute being arranged to deliver contact material into said buckets, upright partitioning within said feed chute dividing it into as many separate feed lanes as there are compartments in each bucket, said lanes corresponding to the compartments in said buckets so that each lane delivers material to a different one of said bucket compartments, duct means extending downwardly from one of said contacting chambers and connecting into only the two lanes delivering into the end compartments of said buckets, duct means extending downwardly from the second of said contacting chambers and connecting into only the remaining lanes which deliver into the compartments lying between the end compartments in said buckets, a discharge chute connected into said elevator casing near its upper end on the opposite side from said feed chute, said discharge chute being arranged to receive contact material discharged from said buckets, upright spaced partitioning in said discharge chute dividing it into as many discharge lanes as there are compartments in each bucket, said lanes corresponding to the compartments in said buckets so that each lane receives contact material from only one of said compartments in each bucket, members defining a passageway for contact material flow from only the two discharge lanes corresponding to the end compartments of said buckets to the second of said contacting chambers, members defining a passageway for contact material flow from only the remaining discharge lanes to the first of said contacting chambers.

10. The method of operating a cyclic process for conversion of hydrocarbons in the presence of a moving contact material which comprises, passing said contact material through a conversion zone wherein it contacts said hydrocarbons under conversion conditions to effect the conversion thereof and through a regeneration zone wherein it is regenerated at an elevated temperature, withdrawing a stream of used contact material from the conversion zone, withdrawing a stream of regenerated contact material from said regeneration zone, continuously dividing and collecting said streams of used and regenerated contact material simultaneously into successive small portions, conveying the portions of used

and regenerated contact material collected simultaneously together in conductive heat transfer relationship with each other through a confined conveying zone, all of the successive portions being successively conveyed in like manner, continuously merging the successively conveyed portions of used contact material into a single stream and passing said stream to the regeneration zone, and separately continuously merging the successively conveyed portions of regenerated contact material into a single stream and passing said last named stream to said conversion zone.

11. In a system for conversion of fluid hydrocarbons in the presence of a moving contact material the apparatus which comprises in combination: an upright conversion chamber, a separate upright regeneration chamber, an upwardly extending elevator casing having a head portion and a foot portion, an endless series of articulated buckets in said casing, drive chains attached to opposite ends of said buckets to support the buckets and to move them in a closed path forming a loop in both the head and foot portions of said elevator casing, in which path the buckets open upwardly when moving upwardly and are inverted when moving downwardly, partitioning within said buckets to divide each bucket into at least three separate, side by side, contact material carrying compartments, one compartment being at each end of said bucket adjacent its connection to a chain and the remainder of the compartments lying between the two end compartments, members defining feed passageways connecting into the lower section of said casing and arranged to direct contact material flow into said two end compartments of said buckets, conduit means extending downwardly from the lower section of said conversion chamber communicating said chamber only with said feed passageways, members defining a separate feed passageway connecting into the lower section of said casing and arranged to direct contact material flow into only the remaining compartments lying between said end compartments of said buckets, conduit means extending downwardly from the lower section of said regeneration chamber communicating the regeneration chamber with only said last named feed passageway, members defining discharge passageways connecting into the upper section of said elevator casing and arranged to receive contact material discharged from substantially only the two end compartments of said buckets, members defining a passageway for contact material flow connecting only said discharge passageways to the upper section of said regeneration chamber, members defining a separate discharge passageway connecting into the upper section of the elevator casing and arranged to receive contact material discharged from substantially only the remaining compartments lying between said end compartments in said buckets, and members defining a passageway for contact material flow from only said last named discharge passageway to the upper section of said conversion chamber.

12. In a method for transfer of particle-form contact material from two streams of similar material, one stream existing at an elevated temperature substantially above atmospheric temperature and the other stream existing at a temperature also substantially above atmospheric temperature but substantially below that of the first stream wherein the contact material is

transferred from one level to a higher level in a confined conveying zone by an endless series of buckets moved and supported through a closed path forming a loop near the upper end of said conveying zone and a second loop near the lower end thereof by endless chains attached to the two opposite ends of the buckets, each of said buckets being divided into three side by side compartments, one central compartment and end compartments on either side thereof adjacent the two ends of each bucket which are attached to the chains, the improvement comprising: flowing the higher temperature particle-form contact material from said higher temperature stream into the central compartments of said buckets near the lower end of said conveying zone, flowing the lower temperature particle-form contact material from said substantially lower temperature stream into the two end compartments of said buckets where it is in indirect heat transfer relationship with said chains, conveying said higher and lower temperature contact material

upwardly within said conveying zone, and causing the contact material to discharge from said buckets at a location near the upper end of said conveying zone while baffling the flow thereof so that said higher temperature and lower temperature contact material pass separately from said conveying zone.
